UNITED STATES PATENT OFFICE.

GEORGE W. COLE AND CLIFFORD W. COLE, OF CAMDEN, NEW JERSEY.

GATE.

1,324,647.

Specification of Letters Patent.

Patented Dec. 9, 1919.

Application filed September 23, 1916. Serial No. 121,743.

To all whom it may concern:

Be it known that we, GEORGE W. COLE and CLIFFORD W. COLE, citizens of the United States, residing at Camden, in the county of 5 Camden and State of New Jersey, have invented certain useful Improvements in Gates, of which the following is a specification, reference being had thereto to the accompanying drawing.

10 This invention relates to improvements in railway crossing gates and has particular application to a train controlled crossing gate.

15 In carrying out the present invention, it is our purpose to provide a crossing gate which will operate automatically to closed position when a train approaches within a predetermined distance of the crossing and which will automatically open after the train has 20 passed the crossing thereby opening the road, intersecting the crossing, to traffic.

25 Another object of the invention is the provision of an automatic crossing gate which may be automatically illuminated when in lowered position, so that the same will be 30 visible at night, and which may be restored to normal position when the crossing is occupied by a train for a relatively long period of time, thereby preventing waste of 35 current.

With the above recited objects in view and others of a similar nature, the invention consists in the construction, combination and arrangement of parts set forth in and falling 40 within the scope of the appended claims.

In the drawings:

Figure 1 is a vertical sectional view through the casing of one of the gates.

Fig. 2 is a perspective view of a detail of 45 the invention.

Fig. 3 is a diagrammatic view showing the circuit connections.

Referring now to the drawings in detail 50 1 designates a double track designed to accommodate traffic in both directions, and intersecting a highway.

Arranged upon opposite sides of the trackway 1 and disposed across the highway, are gate-mechanisms 2, each embodying a 55 housing 3, carrying a cross shaft 4 arranged at right angles to the trackway. Mounted upon one end of the shaft 4 is a barrier 5 capable of movement across the highway to obstruct the latter. Connected to the shaft 4 within the casing is an arm 6 having the end remote from the shaft formed with a

yoke 7, and pivoted within the yoke 7 and depending therefrom is a rod 8 equipped at its lower end with an armature 9 disposed within the influence of a magnet 10 adapted, 60 when energized to draw the armature downwardly and rotate the shaft 4 so as to lower the barrier. The lower end of the barrier is provided with counter weights 11 whereby the gate may be restored to normal position 65 upon the deenergization of the magnet 10.

Mounted upon the gate or barrier is an electric lamp 12 connected in a local circuit 13 including a switch 14 carried by the armature 9 and adapted to close the circuit 70 when the barrier is lowered to illuminate the gate.

The lines of rails of the tracks have the portions within the zone of the crossing insulated from the remaining portions of said 75 rails, as shown at 15 in Fig. 3 and the corresponding terminals of the magnets are connected with the opposite poles of a battery 16, while the remaining terminals are connected across the lines of rails of the respective tracks at the entrances to the insulated sections of the tracks by conductors 17. Thus when a train approaches the crossing upon either track, the wheels and axles will bridge the insulated track section, thereby energizing both magnets to lower the barriers and hold the same lowered as long as the train is passing through the insulated section, the magnets being deenergized when the train has left the insulated section, thereby permitting the counter weights to restore the gates to normal position. 90

Each of the parallel pair of tracks has an insulated section. A wire 23 leads from the insulated section of one track and connects 95 to the opposite end of the insulated section of the other track, a second wire 22 leads from the same end of the section of the second named track to the other end of the section in the other track. There are two 100 gate operating electromagnetic coils designated 10, one of which is wired to connect the first wire 23 to one side of the battery 16 and the other coil is wired to connect the second wire 22 to the other side of the battery 16, as clearly illustrated in Fig. 3. Thus if a train is approaching on the first track toward the gates, the wheels and axle thereof will bridge the first and second rail of the track and thus close the circuit to the 110 battery 16, as follows:

Current will flow from one side of the

battery 16 by way of a wire 26 to the coil 10 and by way of wire 17 to one rail of the first track where an arrow points to the left. The two rails of this track being bridged 5 by the wheels and axle of the car, current flows to the second rail of this track and by way of wire 23 flows to the second coil 10 and thus to the other side of battery 16. Thus the current flows through the magnets 10 controlling the operation of the two gates 10 and the gates are lowered. The two rails of this track are insulated by the insulators 15, so that as soon as a train passes beyond the second pair of insulators 15, the circuit is interrupted and thereupon the magnets 10 will be deenergized and the gates will be automatically raised.

Similarly, should a train be approaching the gates from an opposite direction from 20 that described concerning the first train as indicated by the arrows to the right, the two coils will again be operated to lower the gates. Current will flow from one side of the battery 16 through one coil 10 and by 25 way of wire 25 to one rail of the second track and the two rails of this track being connected by the wheels and axle of the passing train current will flow from the second rail of this track by way of wire 22, 30 and thence through the second coil 10 back to the opposite side of the battery 16 by way of wire 26. Thus it matters not in which direction the train may be moving, the two gates will be operated so as to be 35 lowered or raised.

In Fig. 1 a battery 28 is shown and one of the terminals 5' connected to the lamp 12 is connected to the battery; the other terminal being secured to the lamp 12 and to 40 the switch 14 on the armature 9; the contact plate 14' is carried by the magnet 10 (see Fig. 1) and the wire 15' connects this plate with the opposite side of battery 28. Hence when the switch 14 contacts the plate 14' 45 the local circuit 13 is closed and the lamp 12 will flash. Should a train run from an opposite direction from that described concerning

the first train the circuit would be closed in a similar manner already described.

A switch 18 is preferably connected in 50 the wires 17 at one of the magnets 10 so that the circuit may be broken manually, to release the barriers, as when a train is to occupy the crossing for a long period of time.

If desired a bell 19 may be located at the crossing and connected with the battery 16 and across the lines of rails of the tracks beyond the entrances to the respective insulated sections, as shown in Fig. 3, so that a 60 signal may be sounded, previous to the lowering of the gates.

We claim:—

1. In a device as described, in combination, a housing, a partition extending horizontally therein between its upper and lower ends, a gate swingingly connected to the upper portion of said housing, the pivot for said gate being located directly above said partition, a solenoid depending from said partition, means carried by said pivot and attracted by said solenoid for operating said gate, a switch below said partition, a pair of feed wires leading from said solenoid and connected to said switch, said wires passing 65 out of said housing.

2. In a device as described in combination, a pair of parallel tracks each having an insulated section, a wire leading from the end 70 of the section of one track and connecting to the opposite end of the section on the other track, a second wire leading from the same end of the section of the first-named track to the other end of the section in the other track, two gate operating electromagnetic coils one wired to connect the first wire 75 to one side of the generator and the other coil wired to connect the second wire to the other side of the generator.

In testimony whereof we affix our signatures.

GEORGE W. COLE.
CLIFFORD W. COLE.
